SWITCH MACHINE FOR RAILWAY SPRING SWITCHES

Oscar S. Field, Rochester, N. Y., assignor to General Railway Signal Company, Rochester, N. Y.

Application November 30, 1940, Serial No. 368,034

8 Claims. (Cl. 246—220)

This invention relates in general to switch lock mechanisms for railway track switches, and has more particular reference to such mechanisms for switches of the lockable spring type.

The invention provides mechanism which in conjunction with a spring buffer and a usual hand operated switch stand, spring-holds the track switch in each of its two extreme positions, subject to operation by hand from either extreme position to the other, with the switch locked in the normal position, and trailable by a car from either position.

One of the objects of the invention is to provide means for unlocking the switch by a train flexing the switch rails in a lateral direction when it begins to trail the switch, and more specifically by changing the lateral flexing movement of the rail to a rotary or turning motion for transmitting such motion parallel with the track to the locking mechanism located adjacent the free ends of the switch points for effecting the unlocking of the switch so that it can be fully trailed by the train.

A further object of the invention is to produce the unlocking of the switch by the first small portion of the total movement of the switch rails, and thereafter to not move the lock bolt any further whereby to prevent moving the lock bolt unduly far from the lock rod.

A further object of the invention is to cause the unlocking of the switch to place an opposing signal at stop.

A further object of the invention is to provide check means for the position of an unlocking cam on its shaft whereby to insure that either it is properly positioned or if, due to creeping of the rails, for example, it is improperly positioned, the opposing signal will nevertheless go to stop.

A further object of the invention is to provide means whereby, in the event the switch, on being trailed, does not unlock, but the lock rod breaks and the switch points move to their other extreme position, upon the switch returning to its former position, an opposing signal cannot be restored to its former clear position to thus indicate that the lock mechanism is out of order.

Another object of the invention is to provide signal control means which operate differently under hand operation of the switch, and operation of the switch when it is trailed due to the fact that when a switch is trailed it fails to reach its hand operated final position by possibly half an inch.

Further objects, purposes, and characteristic features of the invention will appear as the de-

scription progresses, reference being made to the accompanying drawings showing, solely for the purpose of illustration, and in no way whatsoever in a limiting sense, one form which the invention can assume. In the drawings:

Fig. 1 is a wholly schematic showing of a switch locking organization constituting one form of the invention.

Fig. 2 is a top plan view of a switch lock mechanism in accordance with this invention with the cover removed and parts broken away.

Fig. 3 is a section on line 3—3 of Fig. 2, and viewed in the direction of the arrows, with parts shown in elevation.

Fig. 4 is a fragmentary view of part of the hand operating means shown positioned for use with a switch at the left hand end of a siding.

Fig. 5 is a fragmentary view of part of the hand operating means shown positioned for use with a switch at the right hand end of a siding.

Fig. 6 is a sectional view on line 6—6 of Fig. 3, and viewed in the direction of the arrows.

Fig. 7 is a sectional view of a spring buffer employed in the invention.

Fig. 8 is a sectional view on line 8—8 of Fig. 3, viewed in the direction of the arrows.

Referring now to the drawings and first to Fig. 1, there is here illustrated in a wholly schematic manner one form which this invention can assume. The various parts are positioned to facilitate explanation of the functions and operations involved, rather than with the purpose of showing the exact construction employed.

In Fig. 1 is illustrated a stretch of main track, 35 constituted by track rails 1, with a track switch TS, leading to a passing siding, which is constituted by track rails 2. A wayside signal having a main line high signal S1 and a take-siding low signal S2 is provided for west bound traffic, and this signal is controlled in accordance with the position of the track switch, by way of the switch operating mechanism. The switch locking mechanism proper is indicated as enclosed in the dashed rectangle SM.

Associated with the switch locking mechanism SM is a spring buffer SB of a construction to be described below in detail. This buffer, when the switch is operated by hand, moves as a unit 50 but allows trailing of the switch by compression of a spring in the buffer, and after the switch is released, it is returned by the spring to its former position. Between the passing of successive car wheels, however, the switch is prevented from slapping against the wheels by means of

a dash pot means in the buffer, as will appear more fully below.

Associated with the switch locking mechanism is a usual hand operated switch stand, which includes a cam drum 3, operable by a hand lever 4 to move an operating member 5 either toward or away from the track rails, as viewed in Figure 1 of the drawings.

Connected to the track switch is a bell crank 6 pivoted at 7 and carrying a cam including an operating portion 8 and a lost motion portion 9 which latter is concentric with pivot 7. The crank is connected at one end at point 10 to the track switch whereby a car passing from the siding onto the main track flexes the switch rails in a lateral direction and exerts a force on the crank for turning it in a clockwise direction just prior to the time the wheels reach the switch points.

An operating crank pivoted at 11, and biased by a spring 11¹, is in contact with the cam and turns a shaft 12 on which is adjustably fixed a switch unlocking cam 13 having a flat idle portion 14 and an inclined faced portion 15. The shaft 12 also carries an operating cam 16 which is adjustably fixed to the shaft and acts upon turning of shaft 12 to open contacts 17 and 18 and thereby put signal S1 to stop. Spring 11¹ operates to normally force the point rail firmly against the stock rail, so as to maintain adjustment.

Cam 13 operates a roller 19 fixed to the lock bar LB so as to cam the lock bar to the left as, viewed in the drawings, against the compression of a biasing spring 20 whereby to withdraw the lock bolt from the lock rod LR upon the springing of the track rail, as described above.

In this diagrammatic showing the lock rod is shown as two separate rods for the purpose of illustration but in actual construction it is of course but one rod. Furthermore, the detector rod DR is shown as two separate rods but in actual construction it is but a single rod as will appear below.

The contacts 17 and 18 for controlling signal S1 are mounted on a block 21 which is fixed in the mechanism casing. The cam 16 operates on a roller 22 to move a frame member 23, which is pivoted at 24, in a counterclockwise direction whereby to bear against an adjusting screw 25. This screw is carried by a second frame member 26 which is likewise pivoted at point 24 whereby to move the operating arm 27 upwardly and open the contacts against the tension of spring 28.

Frame member 26 is also operated in a counterclockwise direction upon the lock bolt being moved to the left by means of a cam face 29 operating on a roller 30, fixed to the operating arm 27. The cam face 29 is carried on a bar 31, bearing against a portion 31¹ of the casing of the mechanism, and is connected to move with the lock bolt by means of rivets or the like 32.

This bar 31 has a notch 33 having an upwardly inclined end 34 for a purpose to be described later.

As thus far described, upon a train making a trailing move the switch rails are first flexed to cam the lock bolt out of engagement with the lock rod and by means of cam 16 to put the signal S1 to stop before the unlocking of the mechanism has been completed and to hold it at stop after the unlocking has been completed by means of the cam 29 of the upper face on the cam bar.

Should the connection between the track rails and the unlocking cam creep or wear so as to produce play therein, it is possible that the unlocking cam might get out of adjustment and

fail to completely unlock the mechanism since a considerable effort is necessary to move this unlocking cam against the effort of spring 20. In case of such creeping, the cam 16 will, however, move and open the signal contacts 17 and 18 to put signal S1 to stop and thus safe-guard traffic despite any lack of initial adjustment of the unlocking cam.

Upon the switch points being moved to reverse position by a train making a trailing move, the detector rod DR is moved with the switch points to cause a cam notch 35 therein to move away from a roller 36 and thus force a bar 37 to the left. This bar carries a cam face 38 which operates, when moved to the left, on a roller 39 to maintain the normal contacts 17-18 in an open position. The bar 37 carries a latch 40, pivoted at 41, and urged in a clockwise direction by a spring 42, bearing at one end against a portion 43 of the housing. The latch has a horizontal arm 44 resting on a portion 45 of the housing whereby, unless otherwise prevented, upon the detector rod moving with the switch points to reverse position, bar 37 is forced to the left and latch arm 44 drops to butt against the fixed shoulder 46. This prevents the return of the bar under the influence of spring 42 when the detector rod has been returned with the switch points to normal position, and thus clearing of signal S1 is prevented.

In normal operation, before the detector rod has moved to reverse position, bar 37 has moved with the lock bolt to position its top face 47 under a roller 48, carried by the latch arm 44, whereby to prevent the latch from becoming operative and holding signal S1 at stop after the switch has returned to normal position.

In the event, however, that on a trailing move the switch is not unlocked before being thrown, it may occur that the lock rod will break off, and the switch will be thrown to reverse position so as to move the detector rod to reverse position. In this case, since the lock bolt has not been operated properly the support face 47 will not be positioned to prevent latch arm 44 from becoming effective. Thus, on the switch returning to normal position, signal S1, which should be clear under such condition, will remain at stop and thus indicate that the switch lock mechanism is out of order.

When the switch is trailed it is not moved to the extreme position that it reaches when operated by hand and fails to reach this position by possibly half an inch. Thus, on trailing, a cam notch 49 in the detector rod fails to move opposite a roller 50 on a spring pressed arm 51 which operates when the notch is opposite it to close contacts 52 and 53 and place the lower arm signal S2 at clear. Accordingly a train, on leaving the siding, places the high signal at stop and leaves the low signal at stop when it is making a trailing move.

The switch can also be operated by hand by means of the hand operated switch stand having the operating handle 4. Assuming that the switch is to be thrown by hand to its reverse position, the handle 4 is moved substantially 180° to the left to thereby move the hand-throw rod HTR. This rod has a pin 55, carrying a roller 56, operating against a hand unlocking cam HUC, pivoted at 57, and operating on a pin and roller 58, carried by the lock bolt LB, whereby to unlock the machine. During this unlocking movement a pin and roller 59 on the hand-throw rod moves upwardly along a vertical cam face 60 in an operating cam OC pivoted at 61. Also, received in

the operating cam is a pin and roller 62 carried by the switch throw rod TR. Due to this vertical cam face 60 the throw-rod is locked against all movement during the unlocking, and thus prevents any springing of the switch points at this time so as to prevent undue friction between the lock bolt and the lock rod.

After the unlocking has been completed, roller 59 is beyond the vertical cam face 60 and enters the portion 63 of the cam opening. This permits the operating cam OC to swing on its pivot and move the throw rod and with it the switch points. In this operation the spring buffer SB moves as a unit, that is, as a rigid portion of the throw rod as will appear more clearly from the discussion below.

Upon moving the switch points by the hand-throw lever to reverse position, signal S1 is put to stop as described above, and signal S2 is cleared as described above, since the detector rod moves far enough to cause its notch to move opposite the roller 59 and allow the contacts 52, 53 to close.

The various parts described in connection with this switch lock mechanism with reference to the diagrammatic showing of Fig. 1 are shown in in one of their actual commercial forms in accordance with this invention, in Figs. 2 and 3.

For example, as can be seen in Fig. 3, the mechanism has a housing 64 with a cover 65 and a wire inlet opening 66.

The unlocking cam 13 can be seen to have an idle or lost motion portion 67 at each side of a socket portion 68, with cam faces 69 interconnecting these parts whereby the cam can be swung on its shaft in either direction and produce unlocking. This feature enables the use of the mechanism for either right or left hand switches.

The hand unlocking cam HUC and the operating cam OC are shown in Fig. 5 in the actual positions they occupied in the mechanism when the mechanism is used for a right hand switch, as shown in Fig. 1. These parts will be shifted in position as shown in Fig. 4, when the mechanism is used for a left hand switch, and the fixed pivots for these operating cams can be shifted to various receiving sockets in the mechanism casing, as shown, for example, at 70 and 70a.

Referring now to Fig. 6, the means is here shown for connecting shaft 12 to the unlocking cam 13. Shaft 12 is hollow and carries the housing 11; and this shaft 12 is coupled to a shaft 72 by means of a feather 73 which is pinned to the shaft 72 by a pin 74 (see Fig. 6). The feather 73 fits slidably in slots in the end of the hollow shaft 12 as shown in Fig. 3, to permit a limited amount of endwise movement of said shaft 12 relative to the shaft 72, while causing the shafts to turn together. This slideable universal joint connection between tubular actuating shaft 12 and the lock operating shaft 72 allows the turning movement of the operating shaft 12, which is imparted to it by the displacement of the track rails during the trailing movement of a vehicle, to be communicated to the locking mechanism some distance down the track to substantially the same extent, independently of the shifting of the ties or like displacement in the relative position of the parts, thereby obviating the need for any bed plate or like means for maintaining any particular relationship between the ties supporting the lock mechanism and the actuator.

Referring now to Fig. 7, there is here shown the spring buffer SB such as shown convention-

ally in Fig. 1, as being connected to the switch throw rod TR.

This spring buffer comprises a housing having a liquid receiving chamber 75 and a spring chamber 76 communicating therewith and normally filled with fluid, such as oil or the like. The wall 77 of spring chamber 76 has a port 78 and 79 at each of its ends and extending inwardly of the ends only a short distance. Entering the spring chamber is a rod 80 which is connected to the throw rod, while a connection to housing 81 is connected to the track switch. Within the housing, rod 80 carries two pistons 82 and 83 which are spring pressed away from each other by a strong spring 84 and are anchored from moving further apart than is shown in the drawings by heads 85 and 86 on rod 80. The pistons have ports 87 and 88 normally closed by check valves 89 and 90, having bleed ports 91 and 92 therein, and normally held in closed position by springs 93 and 94.

As described, when the switch is operated by hand, rod 80 and the buffer casing do not move relatively to each other.

Upon the switch being trailed, however, the switch throw rod is held against movement by the various parts connecting it to the hand operated switch stand, whereby the spring buffer must either expand or contract, depending upon the direction of movement of the switch. In such case, the fluid in the spring chamber must pass beyond one or the other of the pistons and can readily do so by opening the check valve at the particular end in question. As the trailing car wheels pass the switch points, and leave them, the tendency of the spring to slap the switch back under the influence of spring 84 is prevented by the check valves closing. Hence, the fluid can reenter the spring chamber only through one of the bleed ports, and thus a strong dashpot damping effect is produced.

Upon the car clearing the switch, spring 84 returns the switch to its former position. The switch first returns very slowly since the piston has moved beyond the large port 78 or 79, as the case may be. Toward the end of the return stroke of the switch, however, the piston moves opposite its large port, thereby to facilitate transfer of fluid past the piston and the switch closes promptly and strongly with a snap.

The above rather specific description of one form of the present invention is given solely by way of example, and is not intended in any manner whatsoever in a limiting sense. It is to be understood that various modifications, adaptations and alterations may be applied to meet the requirements of practice without in any manner departing from the spirit or scope of the invention except as limited by the appended claims.

Having described my invention, I now claim:

1. In track switch operating means, in combination, a track switch movable to normal and reverse position, means locking the switch in one position, means operable by a car approaching the switch in trailing direction to unlock the switch, a signal controlling opposing traffic, means operable upon unlocking the switch to put the signal to stop, and check means operable by trailing movement of the switch points to hold the signal at stop if already at stop, and if not at stop, to first put it to stop.

2. In track switch operating means, in combination, a track switch movable to normal and reverse position, means locking the switch in one position, means operable by a car approaching

the switch in trailing direction to unlock the switch, a signal controlling opposing traffic, means operable upon unlocking the switch to put the signal to stop, check means operable by trailing movement of the switch points to hold the signal at stop if already at stop, and if not at stop, to first put it to stop, and latch means associated with the check means and the unlocking means and operable only if the switch was not unlocked prior to its operation, to prevent the signal from clearing upon the return of the switch to said one position.

3. In track switch operating means, in combination, a track switch movable to normal and reverse position, lock means for locking the switch in one of said positions, a wayside signal associated with the switch, control means operable by a car approaching the switch to unlock the switch and put the signal to stop, check means movable with the switch and operable to put the signal to stop if not already at stop, and to hold the signal at stop when the switch is not in said one position, and means operable to prevent clearing of the signal on return of the switch to said one position only if the signal was put to stop by said check means.

4. In track switch operating means, in combination, a track switch movable to normal and reverse position, lock means for locking the switch in one of said positions, a wayside signal associated with the switch, control means operable by a car approaching the switch to unlock the switch and put the signal to stop, check means movable with the switch and operable to put the signal to stop if not already at stop, and to hold the signal at stop when the switch is not in said one position, means operable to prevent clearing of the signal on return of the switch to said one position, only if the signal was put to stop by said check means, and additional means operable to put the signal to stop on creeping of the switch rails even though the switch remains locked.

5. A locking mechanism for facing point spring switches comprising, locking means located adjacent the ends of the switch points and including a slidable locking plunger, operating means including a rotatable shaft extending along the track for moving said locking plunger a substantial distance to its unlocked position during a much smaller angular movement of said shaft, and actuator means located at some distance down the track and connected to the movable switch points at a distance from their ends for imparting such angular movement to said shaft when the switch points are flexed by a vehicle trailing them, said operating means including slidable connections permitting relative displacement of the parts lengthwise of the track by

shifting of the ties or the like without interfering with the transmission of operating motion from said actuator means to said locking plunger.

6. In a locking mechanism facing point spring switches, locking means adjacent the points of the switch for locking them in their normal position, a rocking cam turnable on an axis parallel to the track and operable when turned a part of a revolution to release said locking means to permit movement of the switch points to their reverse positions, an actuator located at a distance from the ends of the switch points and responsive to the deflection of the switch rails when a train starts to trail the switch points to convert such deflection into a turning motion, and a connecting shaft extending parallel to the rails of the switch from said actuator to said rocking cam and connected thereto through a slideable connection for transmitting the turning motion of said actuator to said rocking cam for unlocking the switch independently of limited changes in the distance between said actuator and said locking means.

7. A locking mechanism for facing point spring switches comprising, locking means adjacent the ends of the switch points and including a locking plunger movable lengthwise of the track for mechanically locking the switch points in one position, cam means acting when turned on an axis substantially parallel with said locking plunger to move said plunger endwise to an unlocked position, an operating shaft extending for a distance along the track and including a driving connection permitting relative movement of parts endwise of said shaft for actuating said cam means to unlock the switch points, and an actuator including a locking cam connected by a sliding bar to the switch points at a distance from their ends for turning said operating shaft through a small angle in response to the deflection of the switch points during the trailing movement of a vehicle, said locking cam acting to turn said shaft to the same extent for movements of said sliding bar to a variable degree beyond a predetermined initial movement.

8. In switch control means, a track switch, a signal, locking means for the switch points mechanically released by a car trailing the switch, circuit controlling means operable by the movement of the switch points from their locked position for putting said signal to stop, and check means rendered effective when said switch points are moved by a train from their locked position without the prior release of said locking means for holding said circuit controlling means in its operated position until manually restored, and thereby maintaining said signal at stop until such manual restoration has occurred.

OSCAR S. FIELD.
